UNITED STATES PATENT OFFICE.

WALTER F. VAN GUYSLING, OF ALBANY, NEW YORK, ASSIGNOR OF THREE-FIFTHS TO FREDERICK TILLINGHAST, OF SAME PLACE.

LUBRICATOR.

SPECIFICATION forming part of Letters Patent No. 595,031, dated December 7, 1897.

Application filed October 2, 1896. Serial No. 607,682. (No model.)

To all whom it may concern:

Be it known that I, WALTER F. VAN GUYSLING, of Albany, in the county of Albany and State of New York, have invented new and useful Improvements in Sight-Feed Lubricators, of which the following is a full and exact description, reference being had to the accompanying drawings, which form part of this specification.

10 My invention relates to improvements in the construction of sight-feed lubricators, particularly to the manner of securing the several parts together and to the mode of introducing a non-removable ball-valve into the 15 lubricant-passage to automatically close the outlet-opening in case the glass tube of the lubricator becomes broken while in use, to facilitate the renewal of the glass tube, and, in the event of the breaking of said tube, to 20 provide an automatic valve that will prevent an outflow of steam through the lubricator.

The object of my invention is to simplify the construction of the device and to render it more effective in its operation. This object I attain by the mechanism shown in the accompanying drawings, in which—

Figure 1 is a side elevation of my invention; Fig. 2, a vertical section at the longitudinal center line, and Fig. 3 a horizontal 30 section at the line X X.

As represented in the drawings, my improved lubricator consists of a bracket A, a removable arm B, attachable to said bracket, and a glass tube C, similar to those commonly 35 used for such purposes. The bracket A consists of a horizontal arm in which a chamber 1 is formed to contain a metallic ball 2, which when a current of steam of sufficient pressure flows through said chamber will be automatically moved into the position indicated by dotted lines in Fig. 1, where it will bear against

40 a valve-seat 3 to close a passage 4, which forms a communication between the chamber 1 and a chamber 5, formed in the outer end of the horizontal arm of the bracket A. A passage 6, leading downward from the chamber 5, forms a communication with the bore of the glass tube C. The inner end of the chamber 1 forms a passage 7, which communicates with

45 a pipe 8, which is coupled to the bracket A and through which the water of condensation

will flow into the lubricator, and lubricant from the lubricator will be conducted therethrough to the required place. The upper wall of the chamber 1 is provided with a shoulder 9, which when a current of steam is escaping through said chamber by reason of the glass tube being broken will deflect the current downward to impinge against the ball-valve 2 and force the latter up the angle 60 10 against the valve-seat 3. The bottom of the chamber 1 has an obtuse V-shaped form, which produces a depression in which the ball or valve 2 will be normally retained. The ball 2 cannot be removed from the chamber 1, it being of greater diameter than the bore of the passage 7. Said ball is embedded in the sand core which forms the chamber 1 in the process of casting the bracket A, and after the casting of said bracket is completed 65 the core-sand can be removed from the casting in the usual manner and the ball 2 will remain loose in the chamber 1 to operate as previously described. By depressing the bottom of the chamber 1 provision is made for 70 allowing said ball to fall below the range of the passages 4 and 7, thereby allowing a suitable tool to be passed through the opening 7 to ream out and face the valve-seat 3 without interfering with the ball 2. In the lower face 75 of the bracket A a groove is formed concentrically to the passage 6 to receive an elastic annulus 11, which forms a cushion for the upper end of the glass tube C. Pendent from the lower side of the bracket A an arm 12 is 80 formed. Said arm is preferably made with an elliptical or oblong cross-section, and its lower end is tapped to receive a screw-bolt 85 13, by which an arm is secured thereto.

B is an arm that is attached to the bracket 90 A by means of the bolt 13. Said arm is provided with a recess 14, which fits loosely on the lower part of the arm 12. A flange 15, which conforms to the opening of the recess 14, projects from the upper face of the arm 95 B and is preferably made of greater height at its rearmost side, so as to give a greater bearing for said flange at the after side of the pendent arm 12 when the parts are secured together.

In the outer end of the upper face of the arm B an annular groove is formed to receive

an annulus 16, which forms an elastic cushion for the lower end of the glass tube C. The arm B is provided with a nipple 17, which projects upward and is provided with 5 a passage 18, through which the lubricant will enter the glass tube C. A lubricant-supply pipe 19 is connected to the arm B and forms a communication with the opening or passage 18.

10 The glass tube C has its opposite ends formed parallel to each other, so as to obtain a true bearing on the elastic cushions 11 and 16. Said tube, being transparent, affords the proper means for determining whether the 15 lubricator is performing its functions in a proper manner.

By unscrewing the bolt 13 a slight distance the glass tube C will be released sufficiently to enable a person to remove it from the lubricator, and another glass tube may be substituted for it without taking the lubricator apart. If the glass tube C is broken to permit an outflow of steam, the current of escaping steam will impinge against the ball 2 25 and force it to roll up the inclined bottom of the chamber 1 into a position where it will bear against the valve-seat 3 and close the passage 4, thereby shutting off the outflow of steam while a new glass tube is substituted 30 for the broken one and restoring the lubricator to a condition for continuing its operation.

After the bracket A has been finished and the annulus 11 fixed therein and the arm B 35 is provided with its annulus 16, the parts should be assembled in the following manner: The arm B should be loosely placed on the lower end of the arm 12 and the screw-bolt 13 inserted in the arm 12 sufficiently to 40 retain the parts together. The glass tube C should then be placed in position so that its corresponding ends will bear against the annulus to which it is appropriated. Then by screwing up the screw-bolt 13 the parts will 45 be bound together to form steam-tight joints between the ends of the glass tube and the respective annuluses. Lubricant can be fed to my lubricator from feeders arranged to supply a required quantity in a given time, 50 or the lubricant can be fed to it by an automatic lubricator, the sight-feed lubricator

showing ocular evidence that a proper quantity of lubricant is being applied to the part to be lubricated.

What I claim as my invention, and desire 55 to secure by Letters Patent of the United States, is—

1. In a lubricator, the combination of a head having a lubricant-passage formed longitudinally therein and a cushioned seat 60 around its outlet-opening; said head having an arm pendent between its opposite ends, a removable arm attachable to the lower end of said pendent arm having a recess adapted to receive the pendent arm and having a standing flange fitted to bear against the after side of said pendent arm; said removable arm having a cushioned seat on its upper face, a glass tube which is securable between said head and removable arm and is fitted to bear 70 upon said cushioned seats, and means substantially as set forth for securing the removable arm to the pendent arm, as herein specified.

2. In a lubricator, the combination of a 75 head provided with a longitudinal chamber whose lower surface is made to form an obtuse V-shaped depression and whose upper surface is provided with a deflecting -shoulder arranged directly over said depression; 80 the said chamber having an outlet-passage provided with a valve-seat near its outer end, and a ball - valve which—being larger than either the inlet or outlet passage—is irremovable from said chamber and is adapted to automatically close—by the pressure of the escaping steam—said outlet-passage, as herein specified.

3. In a lubricator, the combination of a head having a lubricant-passage formed therein and provided with an arm that is pendent therefrom, a removable arm which is attachable to said pendent arm, a glass tube secured between said head and removable arm, and a screw-bolt inserted in said pendent arm 90 and adapted to press the removable arm against the end of the glass tube, as herein specified.

WALTER F. VAN GUYSLING.
